UNITED STATES PATENT OFFICE.

HENRY A. WALDO, OF RENO, NEVADA.

TELEGRAPH-KEY.

SPECIFICATION forming part of Letters Patent No. 406,489, dated July 9, 1889.

Application filed May 5, 1888. Serial No. 272,998. (No model.)

To all whom it may concern:

Be it known that I, HENRY ALLEN WALDO, of Reno, Washoe county, State of Nevada, have invented a new and useful Improvement in Telegraph-Keys in and to the Cut-Off or Circuit-Closer Thereof, which improvement and invention are fully set forth in the following specification, reference being had to the accompanying drawings.

10 The present invention relates, generally, to telegraph-keys, but more particularly to that class of such keys known as "self-closing" keys, wherein the circuit is normally closed by a lever auxiliary to the key proper, and is 15 opened by the operator in the act of placing the finger upon the key to manipulate the same.

20 The invention consists, among other things, in an improved construction of the self-closer, whereby a more efficient operation is effected.

25 As a more ready understanding of the improvement may be had by a detailed description thereof, such description will now be given, reference being made to the accompanying drawings, forming a part of this specification.

30 In said drawings, Figure 1 is a perspective view of a telegraph-key provided with the improved self-closer. Fig. 2 is a side elevation of the same, the self-closer occupying its elevated position, as is the case when the key is being used. Fig. 3 is a cross-sectional elevation of a portion of the key, the self-closer being in its lowered or closed position. Fig. 35 4 is an elevation of a modified form of the self-closer and a change in the manner of mounting it.

40 Referring to said drawings, it is to be understood that so far as the invention is concerned the telegraphic key may be of any of the well-known forms, and that the key therein shown is simply taken for a convenient illustration of the practical application of the improved self-closer thereto.

45 A represents the lever of the key, having its pivots *a* mounted in the ends of the adjustable bearing-screws *b*, and provided with the usual rear adjusting-screw *c*. The extreme forward end of the key has the ordinary finger-piece or button *d*, and intermediate between the latter and the pivots are

located the contacts *e f*, the former projecting from the under side of the lever and the latter extending upward, immediately below the contact *e* and insulated from the key-frame, 55 as usual.

The preferred form of self-closer *B* is illustrated in Figs. 1 to 3, and consists of a pair of arms 10, united together at one end by a head 12, immediately over the breast of the lever 60 *A*. The opposite ends of the arms are perforated, and are adapted to be mounted on the pivots *a* of the lever, as shown. The arms are L-shaped, the short arm of the L terminating in the head 12, from which projects a 65 stem 13, that extends forward over the forward end of the key-lever, and at its end is provided with a laterally-extending arm 14, that overlies the button *d*, and the ends of which in the preferred form project beyond 70 the edges of the button, so that the operator in the act of placing his finger on said button must necessarily insert it between the button and the arm 14 of the self-closer and lift it from its normal position (shown in Fig. 1) to 75 that shown in Fig. 2, thus opening the circuit and keeping it open while operating by reason of the arm 14 resting upon the back of the operator's fingers, as will be explained further. The ends of the arm 10 tend to 80 spring toward the sides of the key-lever *A*, and bear thus frictionally against the ends of the enlarged portions 11 of the pivots *a*, thus insuring metallic connection through the arms 10 of the self-closer. 85

Coacting with the self-closer is a bifurcated spring-contact 15, which is mounted over an insulated piece 16, but in electrical contact with the contact *f*, and consists of a pair of spring-fingers 8, that rise vertically upon opposite sides of the key-lever. The upper ends of the spring-fingers 8 are curved outwardly to allow the lower edges of the arms 10 to pass them, and so as to lie in close frictional contact with the vertical sides of the contact, as 90 shown in Fig. 3. From this construction it results that each time the self-closer is raised out of contact with the spring-fingers, and in falling back in contact therewith its arms slide frictionally against the same, thus serving to keep the points of contact constantly 95 bright and insuring good metallic connection. 100

The head 12 is located far enough above the lower edges of the arms 10 to permit them to have a slight spring action in passing the contact 15, which latter, owing to the fact that 5 the contact between the arms 10 and its fingers 8 is upon their vertical sides, in contradistinction to simply resting upon a flat surface or in a groove, is rendered more effective in closing the circuit, as no dirt or dust 10 can accumulate on the contact to interfere therewith.

To prevent the self-closer B from being thrown back so far as not to fall back automatically into contact with the fingers 8 when 15 the operator's finger is removed from the button, there is provided a suitably-shaped stop C, carried by the key-lever.

It is not essential that the arms of the self-closer should be mounted on the pivots of the 20 key-lever; but, as shown in Fig. 4, said arms may be mounted on an independent pivot 17, projecting from the key-frame. The other construction is to be preferred, as the self-closer may be readily applied to existing instruments at smaller expense. 25

What I claim is—

1. The combination, with a telegraphic key,

of a self-closer consisting of a pair of pivotally-mounted arms having a stem overlying the key-button and a pair of spring-fingers 30 adapted to contact with the sides of the arms of the self-closer, substantially as described.

2. The combination, with a telegraphic key, of a self-closer consisting of a pair of pivotally-mounted spring-arms 10, having a stem 35 overlying the key-button, and a fixed bifurcated contact consisting of a pair of spring-fingers 8, adapted to receive the arms 10 between them and bear against their sides, substantially as described. 40

3. The combination, with a telegraphic key, of a self-closer consisting of a pair of spring-arms 10, pivotally mounted at one end on the pivots of the key-lever and at the other end united in a head having a stem overlying the 45 key-button, and a pair of spring-fingers adapted to contact with the sides of the arms of the self-closer, substantially as described.
